UNITED STATES PATENT OFFICE.

WILLIAM F. KIESEL, JR., OF ALTOONA, PENNSYLVANIA.

JOURNAL-BOX MOUNTING.

Original application filed September 16, 1924, Serial No. 736,933. Divided and this application filed April 29, 1925. Serial No. 26,766.

This invention relates to railway trucks and more particularly to means for mounting journal boxes within the pedestals of such trucks and is a division of my co-pending application Serial No. 736,933 filed September 16, 1924.

It is a general object of the present invention to provide a novel and improved form of journal box mounting for railway trucks.

10 More particularly it is an object of the present invention to provide a novel and improved pedestal adapted to slidably receive a journal box together with a novel means for providing a cushion support between these two parts.

Another object of the present invention consists in the provision of a pedestal providing a slidable mounting for a journal box and having interposed between the journal 20 box and the pedestal head resilient cushioning means so confined that the journal box may be removed from the pedestal while the cushioning means remain in position.

Other and further objects of the invention 25 will become more apparent as the description proceeds, and for a complete understanding of the invention, reference should be had to the following specification taken in conjunction with the accompanying drawings, 30 wherein are disclosed a single exemplary form of the present invention with the understanding, however, that various changes and modifications may be made in the design, arrangement, proportion, shape, size 35 and material of the various parts without departing from the spirit of the invention and the scope of the appended claims.

Figure 1 is a side elevation of a railway truck showing one of the side frames and its 40 accompanying parts in partial vertical longitudinal section;

Figure 2 is a plan view of one end of a side frame showing the pedestal over a journal box;

45 Figure 3 is a vertical section on line 3—3 of Figure 2;

Figure 4 is a side elevation of one of the side frames, one pedestal being shown in central, longitudinal, vertical section;

50 Figure 5 is a plan view looking from beneath one of the pedestals of Figure 4;

Figure 6 is an end elevation of Figure 4; and

55 Figure 7 is a transverse, vertical section on line 7—7 of Figure 4.

It is common practice, in railway car truck construction, to provide on the side frames of the truck, pedestals providing a sliding mounting for the journal boxes of the wheel axle. In order to insure easier riding, springs are usually inserted between the tops of the journal boxes and the pedestal covers or heads, which springs therefore support the truck frames, and thus the cars, from the wheels. In the operation, 65 maintenance and repair of these trucks it often becomes desirable or necessary to replace journal boxes as well as their axles, or to disassemble these parts for repair and consequently when the side frames carrying 70 the pedestal legs are lifted from the journal boxes for any cause the springs drop out of position and added difficulty and delay is necessary upon reassembly of the parts. To avoid these difficulties, to facilitate the use 75 of several springs having a greater total width than the width of the box, and to insure the proper spacing arrangement and tensioning of the springs both while the journal boxes are in position and when they 80 are removed, either accidentally or intentionally, the arrangement of the present invention has been devised.

Referring to the drawings, there is disclosed at 10 any suitable form of side frame, 85 for instance that described in applicant's co-pending application above noted. Two side frames are necessary for each truck and are connected together by the transoms 11. Each side frame is provided at either end with a 90 pedestal 12 and may have an intermediate pedestal, as for instance, where used with a six wheel passenger truck. Each pedestal comprises inner and outer pedestal legs 13 and 14 respectively and a pedestal cover or 95 head 15, all preferably cast integral with the side frame as shown. In horizontal cross section the pedestal legs are substantially U-shaped, comprising the inner side or guide face 16 and the side flanges 17, the sections 100 progressively widening toward the top and the flanges 17 being reinforced at their outer edges by inturned edge flanges 18. The bottoms 19 of the legs are flat and arranged at right angles to the inner faces 16. The inner or guiding faces of the legs composing a pedestal are parallel to each other and their sides are extended laterally to form the side guide flanges 20 having parallel edges.

The pedestal covers or heads 15 constitute the tops of substantially rectangular box-like structures having open bottoms located over the pedestals and formed by extensions 5 from the sides 21 of the side frames, the side covers 22 and the ends 23. For the sake of lightness and to allow for the inspection of the springs over the journal boxes, to be later described, the sides 21 and 22 are provided 10 with the three perforations 24, 25 and 26 having flanged edges to strengthen the metal about the perforations and to prevent cracking of the casting. An inner bridge wall 27 defines the inside end of the box 15 over each pedestal, and a flange 28 at right angles to the guide faces 16 and projecting away from the journal box space and between the outer side walls of the side frames serves to reinforce the pedestal legs 20 and provide flat bearing surfaces 29 for a purpose to be later described. The narrow flanges 30 project inwardly a short distance and then vertically upwardly to form the open bottom side of the boxes over the 25 pedestals and serve as a rigid support and brace for the outer legs.

Between each pair of pedestal legs is arranged a journal box 31 of any desired or conventional type which as is well-known 30 slides between the guide faces 16 of the pedestal legs and has laterally projecting flanges cooperating with the side guide flanges 20 to prevent transverse movement of the journal boxes in respect to the pedestals. Each journal box contains a journal-bearing 32 adapted to be supported from the axle 33 and a suitable waste pocket 34 with lid 35 provided for the supply and retention of lubricant. It is found desirable 40 to line the guide faces 16 to easily adjust for wear and for this purpose there are disclosed liners 36 held in position by having their right angled flanges 37 clamped against the bottoms 19 of the pedestal legs 45 by means of the bottom plate 38 bolted to the pedestal legs by means of the bolts 39 and serving to limit the amount of upward movement of the pedestals in respect to the journal boxes and thus prevent displacement 50 of the boxes from the pedestals.

In the usual practice one or more helical springs concentric with each other are provided between the pedestal head 15 and the top of the journal box, but the number of 55 these springs or nest of springs is necessarily limited by the narrowness of the top of the journal box. In the present construction, however, this difficulty is overcome by providing the bar 40 which rests upon the 60 top of the journal box and is preferably positioned thereon by the flanges 41. This bar extends longitudinally of the side frames and projects beyond the guide faces 16 of the pedestal legs as clearly shown in 65 Figure 1 and provides accommodation for a

larger number of helical springs 42, here shown as three in number, each one being compound, that is, including two or more concentric springs. These springs rest with their lower ends on the top of the bar 70 40 and the top edges of the flanges 41 and are maintained against transverse movement by means of the flanges 30 between which they have a loose fit. They are spaced apart and properly located within the box over 75 the pedestal by means of the spacing lugs 43, cast integral with the pedestal cover or head 15, and fitting between the respective springs.

By referring to Figure 4 it will be seen 80 that there is an opening 44 beneath the end 23 of the box containing the springs and above the face 29 of the flange 28 thru which the bar 40 may be inserted longitudinally to assume the position shown in Figure 1. 85 Therefore, to assemble the device, the springs 42 are placed in position and, if necessary, compressed by any suitable means and the bar 40 slipped in position thru the opening 44, when the springs can be released and 90 will be maintained in position by means of the bar resting upon the top of the journal box. They are properly spaced from each other by the lugs 43 and are limited in movement transverse to the truck by the flanges 95 30 and the narrowness of the top of the box receiving them. They will also remain in position irrespective of the position of the journal box which can be inserted or removed at will, care being taken however, to 100 see that the bar 40 fits between the lugs 41. To complete the assembly the bottom plate 38 will be bolted in position.

It will be seen from the above that the construction is well adapted for casting so 105 that the whole pedestal and its associated parts is integral with the side frame, that the various flanges and bridges constitute adequate reinforcing and strengthening means for all the load carrying parts, that means are provided for inspecting all of the parts without their removal and that a minimum amount of metal or labor for its machining is required. The coil springs 110 can be put under any desired initial compression and retained under this compression by means of the bar 40 so that the pedestals are not lifted too far off of the journal boxes, while at the same time assuring sufficient spring action so that they 115 will seldom be compressed solid by sudden shocks due to inequalities in the roadbed. If a car is accidentally derailed or if a truck must be hoisted for any particular purpose, the coil springs over the journal boxes will 120 always remain in position even tho the journal boxes are removed from the pedestals. Broken coil springs can be readily detected 125 by inspection thru the holes 24, 25 and 26 provided for that purpose, 130

Having thus described the invention, what is claimed as new and desired to be secured by Letters Patent is:

1. In a truck, in combination, a pedestal, 5 legs depending therefrom, a journal box slidable between said legs, a pedestal head, springs directly between said pedestal head and journal box and means directly supported by said pedestal legs to retain said 10 springs under initial tension, said means being interlocked with said journal box.
  2. In a truck, in combination, a pedestal, 15 guide means thereon, a journal box sliding in said guide means, a spring container above said guide means, springs in said container adapted to support said pedestal from said journal box, and resting directly 20 on said journal box and means recessed in said journal box to limit the expansion of said springs when said journal box is removed.
  3. In a truck, in combination, a pedestal, 25 pedestal legs depending therefrom, a journal box guided by said legs, a pedestal head over said journal box, springs between said journal box and pedestal head, a compression member for said springs, and openings in said pedestal to receive said compression member to retain said springs in said head.
  4. In a truck, a pedestal, pedestal legs depending therefrom, a journal box guided by said legs, a pedestal head over said journal box, helical springs between said journal box and pedestal head, a bar, and openings in said pedestal above said legs for the 35 passage of said bar to retain said springs in said head.
  5. In a truck, a pedestal, legs depending therefrom, a journal box guided by said legs,
- a pedestal head over said journal box, spacing lugs integral therewith, helical springs spaced by said lugs, between said pedestal head and said journal box, a bar and openings between said pedestal head and legs to permit the insertion of said bar beneath 45 said springs for the purpose described.
6. In a truck, in combination, a pedestal, 50 legs depending therefrom, a journal box guided by said legs, an open bottom box formed by said pedestal, a cover thereon, springs interposed between said cover and journal box and housed in said box, and inspection openings in the sides of said box, one adjacent each spring.
7. In a truck, in combination, a pedestal, 55 legs depending therefrom, a journal box guided by said legs, an open bottom box formed by said pedestal, a cover thereon, springs interposed between said cover and journal box and housed in said box, spacing 60 members for said springs on said cover, and flanges on said pedestal forming the sole guides for the lower ends of said springs.
8. In a truck, in combination, a pedestal, 65 guide means thereon, a journal box sliding in said guide means, a spring container above said guide means, springs in said container adapted to support said pedestal from said journal box, a bar interposed between said journal box and springs to retain said 70 springs in said head when said journal box is removed, means on said journal box to prevent lateral movement of said bar and means to permit longitudinal withdrawal of said bar from said pedestal.

In testimony whereof I hereunto affix my signature.

WILLIAM F. KIESEL, JR.
